Primary Examiner — Kimberly Barnes*Assistant Examiner* — Alexandria Dubus(74) *Attorney, Agent, or Firm* — Egbert, McDaniel & Swartz, PLLC(57) **CLAIM**

The ornamental design for a basket, as shown and described.

DESCRIPTION

FIG. 1 is an upper perspective view of a basket showing my new design.

FIG. 2 is front view thereof, a rear view being identical;

FIG. 3 is a side view thereof, an opposite side view being identical;

FIG. 4 is a top plan view thereof; and,

FIG. 5 is a bottom plan view thereof.

The broken lines illustrate portions of the basket that form no part of the claimed design.

1 Claim, 5 Drawing Sheets(56)
